UNITED STATES PATENT OFFICE.

CHARLES R. LAW, OF MANSFIELD, LOUISIANA.

RERAILING FROG.

Application filed March 22, 1924. Serial No. 701,031.

To all whom it may concern:

Be it known that I, CHARLES R. LAW, a citizen of the United States, residing at Mansfield, in the parish of De Soto and State of Louisiana, have invented certain new and useful Improvements in Rerailing Frogs, of which the following is a specification.

This invention relates to new and useful improvements in rerailing frogs.

One object of the invention is to provide a rerailing frog of the character described designed to be used for replacing the trucks of derailed railway cars onto the track.

Another object of the invention is to provide specially designed frogs to be used in pairs for replacing trucks of cars, which have been derailed, onto the tracks from either side.

Another object of the invention is to provide replacers, or frogs of the character described which are comparatively light so that they can be easily handled by one person and whose parts are so arranged and proportioned that they will be strong and not liable to breakage and furthermore will be liable to be displaced by the car wheels during the rerailing operation.

With the above and other objects in view the invention has particular relation to certain novel features of construction, operation and arrangement of parts, an example of which is given in this specification and illustrated in the accompanying drawings, wherein:

Figure 1 shows a plan view of the section of the railway track showing two pairs, or sets of the replacers in position for replacing the trucks of derailed car from either side of the track.

Figure 2 shows a plan view of the outside frog.

Figure 3 shows a sectional view thereof taken on the line 3, 3 of Figure 2.

Figure 4 shows an inside view of the outside frog.

Figure 5 shows a plan view of the inside frog.

Figure 6 shows a front end view thereof.

Figure 7 shows an outside view thereof, and,

Figure 8 shows a bottom plan view of said frogs.

Referring now more particularly to the drawings, wherein like numerals of reference designate similar parts in each of the

figures, the numeral 1 represents the railway ties and the numerals 2, 2 designate the rails thereon. The numeral 3 designates the body of the outside frog and the numeral 4 indicates the body of the inside frog. Each of these frogs is formed with an overlying flange 5 whose free edge is turned downwardly forming a rail-receiving notch into which the tread of the rail fits when the replacer is in position and by means of which the replacers are locked to the rails. The body of each replacer is cast hollow and formed with a vertical flange 6, adjacent the rail whose lower edge rests upon the adjacent rail flange, to assist the ties in sustaining the weight of the car while the same is being replaced.

The opposite side 7 of each frog is given a slight inclination from the rail so as to form a wide base for the frog to prevent its overturning on account of the lateral pressure of the wheels. The respective ends of the frogs rest upon adjacent ties and are formed with depending teeth 8 which bite into said ties and prevent slipping of the replacers.

The tops of the frogs incline upwardly from their rear to their forward ends. The outside frog has a diagonal upstanding rib 10, whose rear end is spaced from the rail and whose forward end is turned into alignment with the rail and forms the forwardly extending projection 11 which lies on the rail tread and gradually declines.

Each inside frog has an upstanding elongated rib 12, aligned parallel with and spaced from the inside of the adjacent rail. Offset from the forward end of this rib and aligned above the rail there is a supplemental rail tread 13 which extends forwardly forming the declining projection 14 in alignment with and similar in contour to the projection 11.

The parts of each frog hereinabove described are cast integral, excepting the teeth 8 which may be driven into suitable sockets provided for them.

In use, a set or pair of the frogs is positioned in front of the wheels to be replaced. The pull on the car is exerted along the central line of the track and the flanges of the outside wheel pass up along the inner side of the rib 10, the flanges of the inside wheel passing up along the inner side of the rib 12. Said wheels are thus gradually elevated and moved over into alignment.

ment above the tracks or rails, the wheel treads gradually assuming a position, one on the rib 15 above one rail, and the other on the supplemental tread 13 above the other rail and said wheels then moved forwardly, gradually moving down onto the rails over the declining projections 11 and 14, without any considerable jar and without displacing the replacers. It often happens that the trucks at one end of the car will be derailed on one side and the trucks at the other end of the car will be derailed on the other side, the car thus standing diagonally across the track. In such case 10 two pairs of replacers will be used and positioned as shown in Figure 1. Both the front and rear trucks may be thus simultaneously replaced on the track at one operation.

20 It often happens that only the rear pair of wheels in a truck become derailed and conditions will not permit placing frogs between the derailed wheels and those remaining on the rail. In such cases the replacers are placed ahead of the wheels remaining on the rail. With the forward movement of the car the wheels pass over the re-placers, the wheel flange, on side of truck where inside frog is placed, passing 25 through the groove 15 between the rib 12 and the supplemental tread 13 which is offset thereto. On the outside frog the overlying flange 5, the upstanding rib 10 and the extending projection 11 maintain the alignment of wheel with the rail. With the passing of the forward wheels over the frogs, the derailed wheels following are picked up and deposited on the rail.

What I claim is:—

40 1. Car replacers including two members having upper inclined faces and formed at corresponding sides to engage over the treads of the rails of a railway track, a

single diagonal upstanding rib formed on the upper face of one member, whose upper end is turned into alignment with the underlying rail and extended forming a declining forward projection, said rib and projection forming a continuous tread for the car wheels, an upstanding rib formed on the upper face of the other member parallel with the adjacent rail, and a supplemental tread formed on the last mentioned member and offset with respect to said last mentioned rib and aligned with the underlying rail and extended forming a declining forward projection.

2. Car replacers including two members each formed of one piece and having upper inclined faces, integral lugs formed at corresponding sides of the member to engage over the treads of the rails of a railway track, a diagonal upstanding rib formed on the upper face of one member, whose upper end is turned into alignment with the underlying rail and extended forming a forward projection, said rib and projection forming a continuous, smooth wheel tread, an upstanding rib formed on the upper face of the other member parallel with the adjacent rail, and a supplemental tread formed on the last mentioned member aligned with the underlying rail, the rear end of the supplemental tread being spaced laterally from the forward end of the last named rib and said supplemental tread being extended forming a forward projection, said projection declining forwardly.

In testimony whereof I have signed my name to this specification in the presence of 80 two subscribing witnesses.

CHARLES R. LAW.
